UNITED STATES PATENT OFFICE.

WILLIAM D. TICKNER, DECEASED, LATE OF JACKSON CENTER, OHIO, BY FRANK BAUGHMAN, ADMINISTRATOR, OF JACKSON CENTER, OHIO.

TRAIN-CONTROLLED CROSSING GATE.

Application filed February 5, 1926. Serial No. 86,219.

The present invention pertains to gates for guarding railroad crossings; and it contemplates the provision of an equipment, easy and inexpensive of installation and reliable in operation, whereby a railroad crossing gate is controlled by a train traversing the crossing; the scheme of the invention contemplating the lowering of the gate by the presence of the train at a point sufficiently remote from the crossing, and the release of the gate when the train reaches a point sufficiently remote from and beyond the crossing.

Another object of the invention is the provision of means complementary to the gate whereby when released the gate will gravitationally return to an idle position so as to clear the crossing and be in readiness for another operation.

Other objects and practical advantages of the invention will be fully understood from the following description and claims when the same are read in connection with the drawings, accompanying and forming part of this specification, in which:

Figure 1 is a view illustrating the gate of my improvement in closed position.

Figure 2 is a plan view showing two gates of my invention and designed to be controlled and operated by train action in accordance with my invention.

Figure 3 is a detail view partly in section and partly in elevation illustrative of the electro-mechanical means for bringing about closing of a gate.

Figure 4 is a perspective of the armature element comprised in said electro-mechanical means.

Figure 5 is a view similar to Figure 3 but illustrating the electro-mechanical means for releasing the gate after a train has traversed the crossing.

Similar numerals of reference designate corresponding parts in all of the views of the drawings.

At 1, are illustrated the rails of a railway and at 2, is shown a highway intersected by the said railway, while at 3 and 4 are shown posts at opposite sides of the highway, the posts 3 at one side of the highway serving for the pivotal connection of crossing gates 5 which are located at opposite sides of the railway and are provided with the comparatively

heavy arms 6 so that normally they will be returned to and maintained in idle and substantially upright position.

The gates 5 are shown as equipped with alarm bells 7, and with incandescent electric lamps 8, but these appurtenances are not of my invention and may therefore when deemed expedient be altogether omitted from the gates without affecting my invention.

The posts 3 and 4 are of hollow formation, Figures 3 and 5, and housed in the posts are the electromechanical means comprised in the invention. The gate equipment and the release means associated with the gates are identical in construction, and therefore, the electro-mechanical means for lowering one gate and the electromechanical means for releasing the same gate will when fully described, be sufficient to impart a definite understanding of the control and operation of both gates.

Referring, therefore, to Figure 3, it will be understood that the pivot of the gate 5 in said figure is in the form of a trunnion 8, journaled in appropriate bearings in the post 3; and it will also be understood that on the said trunnion 8 is fixed an armature 9. It will also be understood that housed with the armature 9 in the post 3 and opposed to the said armature 9 is an electromagnet 10, the winding of the said electromagnet 10 being electrically connected by wires or other appropriate conductors 11 with spaced terminals 12 located at one side of and at a sufficient distance from the highway 2. It will therefore, be seen that the electromagnet 10 is comprised in a normally open electric circuit, and at this point I would have it understood that the electric energy necessary to my improvement may be arranged in fixed relation to the gate location 5 or may be carried on a train, as dictated by the discretion of the manufacturer, the scheme of my invention contemplating the supply of current to the magnet 10 when one or more brushes on a train are in contact with one or more of the shoes 12. Thus with the source of electric energy carried by the train the winding of the magnet may have one terminal connected with a shoe 12 and its other terminal grounded, so that the supply of current to the magnet will bring about energization of the latter, or if preferred the shoes 12 may be arranged in a normally open elec-

tric circuit with the magnet and a source of energy so that when the circuit is completed by a train device bridging the shoes 12, the energization of the magnet 10 will be brought about. In either case it will be readily understood that upon energization of the magnet 10 and the attraction of the armature 9 to said magnet, the gate will be lowered against the action of its comparatively heavy arm 6 to the working position shown in Figure 1.

It will also be understood that upon interruption of the electric circuit alluded to, the electromagnet 10 will be deenergized, and hence will not interfere in any measure with the raising of the gate by the gravitational action of the arm 6.

Housed in the post 4 is an electromagnet 20, and arranged in opposed relation to the said magnet 20 is an armature 21 movable rectilinearly and carried at the inner end of a rod 22, the outer end of which is shaped to form a beveled latch head 23. Surrounding the rod 22 and interposed between the latch head 23 and the adjacent wall of the post 4 is a coiled spring 24, the function of which is to yieldingly maintain the head 23 in the position shown in Figure 5, and to return said head to said position when the magnet 20 is deenergized.

At the right of Figure 2, are shown in the railway and between the rails thereof shoes 30 spaced apart and connected by conductors 31 with the winding of the electromagnet 20. When this arrangement is adopted and a source of electric energy is arranged in the normally open circuit including the magnet 20 and the shoes 30, it will be understood that bridging of the shoes 30, that is to say, the electric connection thereof will be attended by completion of the circuit and by energization of the magnet 20 whereupon the armature 21 will be attracted to the magnet, and the gate 5 will be released from the latch into which the gate had previously engaged, the said release being effected in order that the gate may be returned to its normal idle substantially upstanding position by the gravitational action of the comparatively heavy arm 6 of the gate it is preferred in association with the gate 5 and the latch or latch head 23 to employ an appropriate guard 40 on the post and opposite the forward end of the latch head 23. The said guard 40 will operate on downward movement of the free end of the gate to assure proper cooperation between the gate and the latch head 23 for the inward movement of the said latch head 23, and this against the action of the spring 24 so that after the gate portion has reached a position below the latch head 23, the spring 24 will operate to return the latch head to normal position and enable the same to positively retain the gate in the closed position. When, however, by

train action the circuit including the winding of the magnet 20 is completed, the armature 21 will be attracted to the magnet, and the latch head 23 will be retracted and the gate will be released, and then the gate will, by the gravitational action before alluded to, be returned to and will be yieldingly maintained in its upstanding idle position so as to leave the highway 2 clear. It will also be understood here that when deemed expedient the source of energy may be carried on a train, and a single shoe 30 may be employed in electrical connection with the winding of the magnet 20, and the said winding of the magnet 20 may be grounded in any appropriate manner, so that when a brush on the train is in contact with the shoe, the magnet 20 will be energized for the described release of the gate 5.

It will be apparent from the foregoing that there is provided a train controlled crossing gate equipment that is easy of installation, is inexpensive, and is so reliable in operation as to recommend its employment for the important purpose of guarding grade crossings.

By virtue of the electromechanical means of the improvement being housed in hollow gate posts as illustrated and described, the said electromechanical mechanisms are protected against the weather and against mischievous tampering without the employment of any extraneous means such as auxiliary casings which in addition to increasing the cost of insulation would be objectionable because of the increased extent entailed in the provision of the same.

The present and preferred embodiment of the invention in all of its details has been described in order to impart a full, clear and exact understanding of said embodiment. It is not desired, however, to be understood as confining the invention to the specific construction and relative arrangement of the parts as disclosed, the invention being defined by the appended claims within the scope of which changes in structure and changes in arrangement may be made without departure from the invention.

Having described the invention, what is claimed and desired to secure by Letters Patent, is:—

1. The combination of posts located at opposite sides of a highway intersecting a railway, a crossing gate pivotally connected with one of said posts, electromechanical means for moving the gate from either position to working position, said electromechanical means operable by a train approaching the crossing, and being associated with one of the posts, means tending when the gate is released to move the gate to idle position, means associated with the other post for detachably securing the gate in working position, and electromechanical

means complementary to such other posts for releasing the gate and permitting of the same being moved to idle position; the last named electromechanical means being operable by a train as the train is moving away from the crossing.

2. The combination of posts located at opposite sides of a railway crossing, said posts of hollow formation, a crossing gate arm 10 ranged alongside of one of said posts and having a trunnion journaled therein and also having a comparatively heavy arm, an armature fixed to and movable with said trunnion, and located and movable in the post, an electromagnet also located in the post and arranged in opposed relation to said armature whereby energization of the magnet will be attended by lowering of the gate to working position, and electric, train 15 controlled means for bringing about energization of the magnet when a train is at a predetermined distance at one side of the crossing, with electromechanical means in

and on the other post for latching and retaining the gate when the same is moved 25 to working position, and electromagnetic means whereby when a train reaches a predetermined point beyond the crossing the gate will be by train controlled electric action released.

3. The combination of a hollow post, a guard on said post and exterior thereof, a gate movable vertically to and from a position between the guard and the adjacent portion of the post, an electromagnet in the 30 post, a rectilinearly movable rod guided in the post and having within the same an armature opposed to the electromagnet and also having exterior of the post and between the same and the said guard a beveled head, 35 and a spring interposed between said head and the adjacent side of the post.

FRANK BAUGHMAN,
Administrator of William D. Tickner, deceased.
